UNITED STATES PATENT OFFICE

BENJAMIN F. FITCH, OF GREENWICH, CONNECTICUT, ASSIGNOR TO MOTOR TERMINALS COMPANY, OF WILMINGTON, DELAWARE, A CORPORATION OF DELAWARE

MEANS FOR HOLDING DEMOUNTABLE BODIES ON VEHICLES

Application filed December 5, 1930. Serial No. 500,159.

My prior Patent No. 1,772,939 shows and claims an apparatus for transporting freight by means of a demountable body adapted to be placed on a vehicle and held in position by coacting positioning devices on the vehicle and body comprising upstanding projections arranged on the vehicle entering socket members formed in the base of the body. The object of the present invention is to provide the projection member for the vehicle so formed that it may be readily mounted on the wooden floor of a flat car over a sufficient area of the floor planking to insure the positioning projection being firmly held and retained in the desired position, and to properly distribute the weight of the loaded body so as to avoid injuring the wooden floor of the car. My positioning members are so mounted that at any time they may be removed, and leave the car floor suitable for its original purpose.

To the above end, I provide the positioning member illustrated in the drawings hereof, and hereinafter more fully described and set out in the claims.

In the drawings, Fig. 1 is a side elevation of a flat car equipped with my positioning members for holding two demountable bodies, one of such bodies being shown in place; Fig. 2 is a plan of the flat car and body shown in Fig. 1; Fig. 3 is a plan on a larger scale of one of the positioning members and a portion of the car floor; Fig. 4 is a vertical section through the positioning member and car floor, in a plane indicated by the line 4—4 on Fig. 3.

As shown in Figs. 1 and 2, A indicates a suitable flat car having a wooden floor and B a demountable body adapted to be placed thereon. This demountable body has downwardly facing sockets b (Fig. 4) in its base adapted to coact with the projections constituting the present invention.

The projecting positioning member of this invention is designated as a whole by the numeral 10. It comprises a comparatively large base plate 11, preferably square, to which is rigidly attached a sur-base 12 of quadrant shape, from which rises a cylindrical projection 13 terminating in a conical end por-

tion 14. The sur-base 12 preferably has a depressed region 15 surrounding a higher flat region 16 which extends in a horizontal plane from the bottom of the cylindrical portion.

The cylindrical portion, the conical portion and the sur-base may readily be a single casting and this member may be electrically welded to the larger base plate 11. The plate 11 is provided with suitable holes 17, through which may pass bolts 20 extending through the wooden floor of the car. I have shown four of these bolts adjacent the four corners of the base 11. By reason of the supporting surface 16 on which the demountable body rests, being at a higher elevation than the extended base 11, the heads on the bolts may be of considerable size and still clear the body.

The extended base plate 11 and the strong bolts at a considerable distance from each other resist any possible tendency of the positioning member to be tipped up about one edge due to a swinging motion of the body being lowered or to a lateral stress during travel. Some latitude is allowed in placing the positioning members on the floor of the car—they may be skewed, if necessary, about the axis of the projection, or the whole set shifted longitudinally so that there is never any necessity for the bolts passing in a crack between adjacent planks.

It will be seen that the projections may be readily secured to any existing flat car of proper dimensions. When so secured they provide very effective means for bringing to position a body being lowered and holding it against shifting, they also provide flat surfaces 16 of considerable extent on which the demountable body rests so that no damage can be done to the intermediate region of the floor if it should bow up to some extent between the positioners. At least four of these positioners are employed adjacent the four corners of the rectangular region to be occupied by each body, but I prefer to add two intermediate positioners set inwardly of the sides of such rectangle in the mid region, as illustrated in Fig. 2.

The annular depressed region 15 about the plane surface 16 of the positioner provides space for suitable marking, such as the name

of the manufacturer or owner, patent number etc.

I claim:—

1. A device for holding demountable bodies on vehicles comprising a member having an upstanding body with a tapered top, said member having a base projecting to a considerable extent in all directions and means engaging the projecting base for holding the device in place.
2. The means for holding demountable bodies on vehicles comprising a member having an upstanding body terminating in a substantially conical top, said member having a base projecting to a considerable extent in all directions and provided with openings for the passage of fastening devices.
3. A positioning device suitable for mounting on the floor of a flat car and comprising an extended flat base plate having openings for the passage of fastening devices, a surmounting base of smaller contour rigidly secured to the first mentioned base and having a horizontal seating surface above the top surface of the first mentioned base, and an upward projection on the surmounting base.
4. The combination with a flat car having a wooden floor, of a positioning device comprising a plate carrying an upwardly extending projection terminating in a substantially conical top, there being a plurality of openings through the base, and bolts passing through said base into the wooden floor of the car.
5. A positioning device comprising a steel casting with a base, a cylindrical body and a conical top and an extended base plate to which said casting is rigidly secured.
6. A positioning device of the character described, comprising an extended base plate having openings for the passage of fastening devices, a surmounting base of considerably less area, rigidly secured to the main base inside of the region defined by said openings, a projection rising intermediately from said surmounting base and leaving a flat margin above the projection a material distance above the top of the base plate, said projection having a conical top.
7. A positioning device of the character described, comprising an extended base plate having openings for the passage of fastening devices, a surmounting base of considerably less area, said surmounting base being rigidly secured to the main base inside of the region defined by said openings, said surmounting base having a depressed margin and a flat portion in the inside of the margin, and a projection rising intermediately from the flat portion.

In testimony whereof, I hereunto affix my signature.

BENJAMIN F. FITCH.
